(57) **CLAIM**

The ornamental design for a welding device, as shown and described.

DESCRIPTION

FIG. 1 is a top perspective view of a welding device, according to a first embodiment of the present invention; FIG. 2 is a bottom perspective view of the welding device of FIG. 1;

FIG. 3 is a front view of the welding device of FIG. 1; FIG. 4 is a rear view of the welding device of FIG. 1; FIG. 5 is a right side view of the welding device of FIG. 1; FIG. 6 is a left side view of the welding device of FIG. 1; FIG. 7 is a top view of the welding device of FIG. 1; FIG. 8 is a bottom view of the welding device of FIG. 1; FIG. 9 is a top perspective view of a welding device, according to a second embodiment of the present invention; FIG. 10 is a bottom perspective view of the welding device of FIG. 9;

FIG. 11 is a front view of the welding device of FIG. 9; FIG. 12 is a rear view of the welding device of FIG. 9; FIG. 13 is a right side view of the welding device of FIG. 9; FIG. 14 is a left side view of the welding device of FIG. 9; FIG. 15 is a top view of the welding device of FIG. 9; FIG. 16 is a bottom view of the welding device of FIG. 9; FIG. 17 is a top perspective view of a welding device, according to a third embodiment of the present invention; FIG. 18 is a bottom perspective view of the welding device of FIG. 17;

FIG. 19 is a front view of the welding device of FIG. 17; FIG. 20 is a rear view of the welding device of FIG. 17; FIG. 21 is a right side view of the welding device of FIG. 17; FIG. 22 is a left side view of the welding device of FIG. 17;

(Continued)

FIG. 23 is a top view of the welding device of FIG. 17; and, FIG. 24 is a bottom view of the welding device of FIG. 17.
